UNITED STATES PATENT OFFICE.

WALTER H. DIFFENDALL, OF HAGERSTOWN, MARYLAND.

OIL-TORCH.

1,278,381.

Specification of Letters Patent. Patented Sept. 17, 1918.

Application filed April 30, 1918. Serial No. 231,686.

To all whom it may concern:

Be it known that I, WALTER H. DIFFENDALL, a citizen of the United States, and resident of Hagerstown, Maryland, have invented certain new and useful Improvements in Oil-Torches, of which the following is a specification.

The invention is an improvement in oil burning torches for use in heating metals which are to be united or in making repairs in machine shops and for like purposes.

The invention consists in the features and combination and arrangement of parts hereinafter described and particularly pointed out in the claims.

In the drawings accompanying this specification:

Figure 1 is a sectional view of the burner.

Fig. 2 is a plan view of the coil which forms a part of the supply pipe leading to the burner nozzle.

Fig. 3 is a side view of the burner and the means for supplying the same with fuel.

Fig. 4 is a plan view of Fig. 3.

Fig. 5 is a plan view of a modification.

The burner proper includes a shell 1 having a nozzle portion 2, these parts being of tapered form, and I provide any suitable means for removably securing them together, such as the bolts 3 passing through the lugs 4 on said parts. The nozzle portion 2 at its large end fits in a seat formed within the outwardly flared or positioned rim 5 of the main shell portion 1. In rear of the shell 1 and spaced apart therefrom I provide a coil of pipe 6, which forms a continuation of the supply pipe 7 through which a mixture of oil and air are delivered to the burner tip 8, which is formed at the end of the axial extension 9 of the coil of pipe, this tip being directed so that the flame will be projected axially of the nozzle.

The coil, as above stated, is spaced apart from the base of the shell and the tip is substantially in the plane of base line of the shell. The coil is held in this spaced apart relation by clips or brackets 10, extending from the shell to which they are bolted, or otherwise secured, the lower ends of the brackets being inturned and welded to the coil. The coil is of a diameter substantially co-equal with that of the interior of the burner shell and it is in position to receive the back fire or heat from the said shell, so that the oil will be gasified before reaching the burner tip. By having the coil spaced

apart from the rear of the base of the conical shell, or nozzle, complete combustion is secured because the air is free to pass to the burner tip through the space existing between the base of the cone and the coil and the entrance of air may take place from all points around the circumference of the base of the cone.

The position of the coil, however, must bear a certain relation to the base of the cone and not be too far away, because under the latter circumstances the point of combustion would be not well within the cone, but at such a position that the flame would pass out radially from the base of the cone and would not be directed onto the surface to be heated at the nozzle end or small end of the cone.

Further the coil must not be placed too near the base of the cone, as under this arrangement the flame would be suppressed or smothered out when the nozzle end of the cone is positioned close to the surface to be heated, because a proper air supply could not then reach the flame for proper combustion. If the nozzle or small end of the cone is placed very near to the surface being operated on the flame will back-fire freely through the base of the cone and laterally through the space between the coil and the said base and the flame will not smother out but will be maintained.

Some air will reach the point of combustion through the coil. I employ a closely coiled pipe, as this will afford a firm support for the cone, which is attached thereto, and will also provide for a sufficient length of pipe in the coil to insure proper heating of the oil before it reaches the burner tip.

My burner is adapted for use with a high degree of heat, because the coil of pipe being located exteriorly to the base of the cone will not be burned out, because of the high heat of the flame, which it might do were the coil located within the shell or cone.

The cone is made in sections in order that the small or nozzle end may be renewed without disturbing the coil or the base of the shell which may remain attached to each other. Only a single supply pipe leads to the coil, and this is intended to feed air and oil and for this purpose the supply pipe is connected with a tank 11 containing the oil, air under pressure being admitted to the top of the tank through a pipe 12, having a check valve 13 therein, said pipe being

controlled by a globe valve 14. The check valve 13 is adapted to maintain the pressure in the upper end of the tank. Depending into this tank is an oil pipe 15, leading to 5 near the bottom thereof, and connecting with the upper end of this pipe is a suitable fitting, or fittings, having a globe valve at 16, a check valve at 17, and a needle valve at 18, the fitting connecting with a flexible 10 hose 19, which is suitably connected with the coil at the burner.

The tank has also connected therewith a fitting or fittings, communicating with the upper end of the tank, so that the compressed air therein may be discharged 15 through the said fittings and a T 18' connects the oil discharge fitting with the air discharge fitting, so that the air in passing to the flexible hose will have an ejector action 20 on the oil and draw the oil from the tank, this action being assisted by the pressure of the air in the upper part of the tank. A check valve is provided at 20 in the air fitting and a globe valve is provided 25 at 21, controlling the discharge of air from the tank, and another globe valve is arranged at 22 to control the discharge of the mixture of oil and air to the burner. As shown in Fig. 5 the connection between the 30 oil and air pipes may be arranged at the point α remote from the tank and a globe valve may be arranged at 23 and check valves at 24, 25 in the air and oil pipes, respectively, and also globe valves 26 and 27 35 may control the discharge of air and oil from the tank.

In the operation of the apparatus the air is turned on so as to be discharged into the pipe leading to the burner and then the oil 40 is slowly admitted into said conduit or pipe until the mixture appears at the nipple of the torch or burner, which is then lighted. The flame within the cone will create a backfire of flame against the coil and the oil will 45 be vaporized in this coil before reaching the burner tip.

What I claim is:

1. In combination a burner having a coni-

cal nozzle, a burner tip directing its flame axially of the said nozzle, and a coil of pipe 50 in rear of the burner tip to supply the tip with fuel, said coil being coaxially arranged with the nozzle and located outside of the nozzle and spaced apart from the base thereof, leaving a passage for the entrance of 55 air from all sides between it and the base of the burner nozzle, said coil providing a guard extending substantially across the opening at the base of the cone to provide a guard against the backward passage of the 60 flame and allowing lateral passage of the flame when checked at the discharge end of the nozzle, substantially as described.

2. In combination a burner having a conical nozzle, a burner tip at the base of the 65 nozzle directed axially thereof, and a coil of pipe to supply the tip with fuel, said coil being arranged in one plane parallel with and spaced apart from the base of the conical nozzle to provide for the passage of 70 air from all sides to the said tip, said coil providing a guard against backward and lateral passage of the flame under normal conditions, but allowing lateral passage of 75 the flame when the flame is choked at the discharged end of the nozzle, substantially as described.

3. In combination a nozzle, a burner tip 80 axially disposed relative thereto, a coil of pipe connecting with the burner tip and outside of and spaced apart from the base of the nozzle, and a bracket for supporting and spacing the nozzle from the coil, substantially as described.

4. In combination a nozzle formed in sections including a base section, means for removably holding said sections together, a coil outside of and spaced apart from the base section, and means for supporting the base of said nozzle from the said coil, substantially as described.

In testimony whereof I affix my signature.

WALTER H. DIFFENDALL.
